UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ATTACHMENT-PLUG.

1,167,474.

Specification of Letters Patent. Patented Jan. 11, 1916.

Application filed April 19, 1913. Serial No. 762,429.

To all whom it may concern:

Be it known that I, REUBEN B. BENJAMIN, a citizen of the United States, residing at Chicago, in the county of Cook and State 5 of Illinois, have invented new and useful Improvements in Attachment-Plugs, of which the following is a full, clear, concise, and exact description, reference being had to the accompanying drawing, forming a 10 part of this specification.

My invention pertains to attachment plugs, and especially relates to separable attachment plugs—*i. e.*, plugs of the kind which include an insertible member adapted for insertion into a wall socket or the like and a binding-terminal carrying member separably connected with the insertible member.

It is an object of my invention to provide 20 a separable attachment plug of the above character which will be convenient and safe in use, which will be of a simple and durable construction, and may be placed on the market at a low cost.

It is a further object of my invention to 25 improve upon the details of construction of attachment plugs.

A separable attachment plug constructed in accordance with my invention is described, by way of example, in the following specification and shown in the accompanying drawings. It is to be understood, however, that my invention may be embodied in plugs of other kinds than that 30 described and shown, and that changes may be made in the construction which I have chosen as illustrating my invention, without exceeding the scope of the invention as defined in the appended claims.

40 In the drawings: Figure 1 shows a separable attachment plug constructed in accordance with my invention in longitudinal section; Fig. 2 is a plan of the upper end of the insertible member; Fig. 3 is a plan of the lower end of the insertible member; Fig. 4 is a plan of the upper end of the binding-terminal carrying member; Fig. 5 is a plan of the lower end of the binding-terminal carrying member; Fig. 6 is a section on the line 6—6 of Fig. 1 looking in the direction of the arrows; Fig. 7 is a section on the line 7—7 of Fig. 1 looking in the direction of the arrows; Fig. 8 is a per-

spective view of one of the forked contacts of the insertible member; Fig. 9 is a perspective view of one of the plunger contacts of the binding-terminal carrying member; Fig. 10 is a perspective view of one of the retaining plates for the plunger contacts; Fig. 11 shows in longitudinal section a modified form of the insertible member; and Fig. 12 is a plan of the upper end of the insertible member shown in Fig. 11.

Like reference characters refer to like parts throughout the following specification 65 and the several figures of the accompanying drawing.

Referring now to the drawings, the insertible member comprises an insulating block 10, formed with an enlarged disk shaped head 70 11. The block 10 is formed with two downwardly opening chambers 12, each of which contains a forked contact adapted to be engaged by a plunger contact of the binding-terminal carrying member, each forked contact consists of a metallic strip bent to form a pair of resilient arms 13 connected at their upper ends by a transverse portion 14. The arms 13 terminate short of the mouths of the openings 12, and one arm of each pair 80 is provided with a retaining projection 15 adapted to engage in a hole formed in the corresponding plunger contact of the binding-terminal carrying member. Mounted on the upper end of the insulating block 10 85 is an insulating button 16 having a flange 17 which surrounds the top end of the block 10 so as to maintain the button and the block in axial alinement. The button 16 has a hole formed therethrough coaxial with one 90 of the chambers 12. The hole receives the shank 18 of the center contact 19. The shank 18 passes through an aperture in the transverse portion 14 of one of the forked contacts and is riveted over within the 95 forked contact, whereby the forked contact and the center contact are secured in position and the insulating button 16 is secured to the insulating block 10. The insulating button 16 is formed with a second aperture, 100 coaxial with the second chamber 12, which aperture receives a connecting plate 20, the upper end of which is formed with a head 21. The connecting plate 20 passes through a bent metallic strip 22, its head 21 clamping this strip 22 against the bottom of a re-

cess 23 formed in the upper end of the block 16. The lower end of the connecting plate 20 passes through an aperture in the transverse portion 14 of the forked contact and is riveted over within the forked contact, as clearly shown in Fig. 7, whereby the forked contact and the bent strip 22 are secured in position.

10 A cup-shaped conducting member 24 is mounted on the insulating block 10, and rests on a shoulder 25 with which the latter is formed. The strip 22 is hooked, at 26, into the cup-shaped member 24 (Figs. 1 and 2), whereby electrical connection is established between the cup-shaped member 24 and the forked contact which is retained in position by the connecting plate 20. The insulating button 16 is formed with a channel in the side thereof to provide room for 15 the passage of the strip 22.

15 Mounted on the insulating block 10 is a threaded contact 27. The lower end of the contact 27 is flanged inwardly, at 28 so as to engage beneath the cup-shaped member 24 when the plug is inserted into a socket. An 20 insulating thumb ring 29, adapted to be grasped when the threaded contact is to be screwed into or out of a socket, is secured to the lower end of the threaded contact.

25 The binding-terminal carrying member consists of an insulating base 30 having a peripheral flange 31 extending upwardly therefrom, such flange being of sufficient diameter to inclose snugly the disk-shaped extension 11 of the insulating block 10 when the binding-terminal carrying member is attached to the insertible member. The base 30 is provided with two upwardly extending plunger contacts. These plunger contacts being of similar construction a description of one of them will suffice. Each plunger contact includes a flat metallic strip 32 which lies in the bottom of a rectangular depression 33 formed in the upper surface 35 of the base 30. Adjacent the end of the strip 32 which is located toward the center of the base 30, the strip is bent upward and back upon itself to form a V-shaped plunger 34. Beyond the plunger 34, the plate is bent 40 to form a lug 35 which lies in the bottom of the recess 33. The V-shaped plunger 34 has formed therein a hole 36 for receiving the retaining projection 15 of the corresponding forked contact of the insertible member. The metallic strip 32 is formed, at the 45 end thereof remote from the center of the base 30, with an upwardly extending flange 37, and has formed therethrough, at the base of the V-shaped plunger 34, a pair of aligned apertures 38, the bottoms of which apertures are in the same plane as the top surface 50 of the strip. A retaining plate 39 lies on the strip 32 and is provided with a tongue 40 which extends through the apertures 38 and 55 lies upon the lug 35. A screw 41, passing

upward through the base 30, enters the tongue 40, and thereby secures the retaining plate 39 in position, the retaining plate thus clamping the strip 32 against the bottom of the recess 33. The retaining plate is provided with a binding screw 42, to which access may be had by means of a channel 43 leading to an aperture 44 extending downwardly through the base.

70 The apertures 44 open into an internally 75 screw threaded hole formed in the lower part of the base 30. This hole receives a hollow screw threaded bushing 45 through which the conductors 46 may be passed centrally. When the conductors 46 are secured 80 beneath the binding screw 42, they may be clamped in position by screwing the bushing in so that its upper edge will bind the conductors firmly against the lower part of the base 30.

85 The threaded contact 27 being rotatable with respect to the remainder of the insertible portion, it is possible to insert the complete plug into a socket without twisting the conductors. The construction has the further advantage that the portion of the insertible member which carries the forked contacts can be locked in any desired position. When the binding-terminal carrying member is removed from the insertible member, the forked contacts are isolated from each other in such a manner that it would be exceedingly difficult for them to be accidentally bridged or for a person to receive a 90 shock by touching both of them simultaneously. The binding-terminal carrying member may be attached to, or removed from, the insertible member with great ease; and the construction is such that the binding-terminal carrying member will be pulled 95 automatically away from the insertible member in case of any considerable pull being accidentally applied to the conductors, regardless of whether such pull is in line with the axis of the plug or at an angle thereto.

100 In cases where it is not desired to provide the insertible member with a rotatable threaded contact, the insertible member shown in Figs. 11 and 12 may be employed. The insertible member shown in the Figs. 11 and 12 consists of an insulating block 47 formed with a shoulder 48 and an annular flange 49 which may be seized by the fingers when the insertible member is being screwed into or out of a socket. Below the flange 49, the insulating block 47 is formed with a disk shaped extension 50 of a size to snugly fit within the flange 31 of the binding-terminal carrying member. The block 47 is formed with a pair of chambers 51, containing the forked contacts, these chambers and forked contacts being similar to the chambers 12 and forked contacts described above. One of the forked contacts is held in position by means of the shank 52 of a center 115 120 125 130

contact 53 in a manner similar to that in which the shank 18 of the center contact 19 holds the corresponding forked contact in position.

5 A threaded contact 54 surrounds the upper part of the block 47 above and rests upon the shoulder 48. The threaded contact 54 is provided with an inwardly extending flange 55 at its upper end, which flange is formed 10 with a slot for receiving a small boss 56 extending upwardly from the block 47, thereby preventing relative rotation between the threaded contact 54 and the block 47. A portion of the flange 55 is enlarged at 57 15 so as to cover a considerable portion of the top end of the block 47. A securing plate 58 lies upon the enlarged portion 47 and is provided with a shank 59 which extends downwardly through a hole formed longitudinally in the block 47. The shank 59 is riveted over within the second forked contact. Thus the securing plate 58 makes electrical connection between the threaded contact 54 and one of the forked contacts, and 20 at the same time, serves to secure the threaded contact against longitudinal withdrawal from the block 47.

The insertible member shown in Figs. 11 and 12 is of an exceedingly simple and economical construction, and the parts of it may be assembled with great ease and speed. It is adapted to be used in connection with the binding-terminal carrying member described above, with reference to Figs. 1-10.

35 Having thus described my invention, what I claim as new and desire to secure by Letters Patent is:

1. In combination, an insulating base, a metallic strip lying on said base and having 40 a portion thereof bent upwardly and back upon itself to form a V-shaped contact, a retaining plate having a tongue extending through the base of said V-shaped contact, the contact being provided with portions for 45 engaging with said tongue and said insulating base between the two, and means located in the same plane as said V-shaped contact for securing said retaining plate in position.

2. In a separable attachment plug, an insulating member, a substantially U-shaped contact having the portion between its arms secured against said member and its arms free from and spaced away from said member, a second insulating member, a substantially 55 V-shaped contact secured to said second insulating member with the divergent ends of its arms against said second member, the convergent ends of said V-shaped contact extending between and engaging the 60 arms of the U-shaped contact.

3. In a separable attachment plug, an insulating member, a substantially U-shaped contact having the portion between its arms secured against said member and its arms free from and spaced away from said mem- 65

ber, a second insulating member, a substantially V-shaped contact secured to said second insulating member with the divergent ends of its arms against said second member, the convergent ends of said V-shaped contact extending between and engaging the arms of the U-shaped contact, one of said engaging arms being provided with an aperture, and another of said arms having a projection extending into said aperture. 70 75

4. In combination, an insulating base, a substantially V-shaped contact having an aperture in each arm thereof, said apertures being distant from the apex of the V, a retaining member extending through both of 80 said apertures, and means for securing said member to said base.

5. In combination, an insulating base, a substantially V-shaped contact having an aperture in each arm thereof, a retaining 85 member of conducting material extending through both of said apertures, a binding terminal engaging said retaining member, and means for securing said member to said base. 90

6. In combination, a substantially V-shaped contact having an opening in each arm thereof, said openings being distant from the apex of the V, a member of conducting material extending through both of 95 said openings, and a binding terminal engaging said member. 100

7. A separable attachment plug comprising an insulating base having an aperture therethrough, a substantially U-shaped contact of sheet material having an aperture in the part connecting the two arms registering with the first said aperture, and a retaining member of sheet conducting material passing through both apertures, said retaining member having a part extending over the edge of the aperture in the U-shaped member, for holding it in place, said arms and retaining member lying substantially in parallel planes. 105 110

8. In a separable attachment plug, an insulating button having an aperture therethrough offset from the axis thereof, a contact tongue of sheet material having an aperture therethrough in registry with the first said aperture, an L-shaped conducting member of sheet material having one arm extending through both said apertures, and the other arm extending from said offset aperture toward the axis of the button, and means for securing said contact to said member, said tongue and the arm of the member which extends through said apertures lying substantially in parallel planes. 115 120

9. In a separable attachment plug, an insulating button having an aperture therethrough offset from the axis thereof, an insulating member having an aperture in registry with said first aperture, a contact having an aperture therethrough in registry 125 130

with said first and second apertures, an L-shaped conducting member having one arm extending through all of said apertures and the other extending from said offset aperture 5 toward the axis of the button, and means for securing said insulating member and contact to said L-shaped member.

Copies of this patent may be obtained for five cents each, by addressing the "Commissioner of Patents, Washington, D. C."

In witness whereof, I have hereunto subscribed my name in the presence of two witnesses.

REUBEN B. BENJAMIN.
